EDMOND CHABOCHE, OF PARIS, FRANCE.

ROTARY ENGINE.

SPECIFICATION forming part of Letters Patent No. 569,408, dated October 13, 1896.

Application filed August 24, 1894. Serial No. 521,574. (No model.) Patented in France March 17, 1894, No. 237,105; in Belgium July 20, 1894, No. 111,076; in Switzerland July 23, 1894, No. 9,043; in Germany July 27, 1894, No. 82,242; in England August 3, 1894, No. 14,940, and in Austria-Hungary September 3, 1894, No. 1,032.

To all whom it may concern:

Be it known that I, EDMOND CHABOCHE, a citizen of the Republic of France, residing at Paris, in the Republic of France, have invented certain new and useful Improvements in Rotary Engines with a Movable Cylinder, (for which Letters Patent were granted to me in France, No. 237,105, dated March 17, 1894; in Germany, No. 82,242, dated July 27, 1894; in England, No. 14,940, dated August 3, 1894; in Belgium, No. 111,076, dated July 20, 1894; in Switzerland, No. 9,043, dated July 23, 1894, and in Austria-Hungary, No. 1,032, dated September 3, 1894,) of which the following is a specification.

My invention relates to improvements in rotary engines in which any kind of motive fluid may be used, but in which steam is by preference employed; and it has for its object the employment of a movable cylinder having a continuous motion in the same direction and serving the purpose of a fly-wheel, and, further, with some slight change, of a driving-pulley.

My invention consists of a cylinder divided up into compartments, in each of which reciprocates a piston or wing, and all of which are mounted on a sleeve through which passes the shaft of the cylinder, of various cranks and connecting-rods, of a valve with inlet and outlet ports, and of the various parts that will be hereinafter described, and fully pointed out in the claims.

In the accompanying drawings, Figures 1 to 6 are diagrams which illustrate the theory of the movements of my improved rotary engine. Fig. 7 is a vertical longitudinal section of the same; Fig. 8, an enlarged vertical longitudinal section of the distributing-valve; Fig. 9, an end elevation of the engine, showing the face of the cylinder which is in contact with the valve. Fig. 10 is an end elevation of the face of the valve shown detached from the engine; and Figs. 11 and 12 are vertical central sections through the rotary cylinder and the reciprocating pistons, taken at right angles to the plane of Fig. 7 and showing the pistons in operative position in their respective compartments.

Similar letters and figures of reference indicate corresponding parts.

To render the action of the engine clear, a theoretical explanation of the various phases of its movements is first given.

A body 1 of any geometrical figure, as, for instance, a circle, is rotated on an axis 2 3, Fig. 1. This hollow body is divided into equal parts by a certain number of walls, the planes of which when prolonged pass through the axis 2 3. Between the fixed walls 4 5, 6 7, 4' 5', 4" 5", &c., Fig. 2, reciprocate the movable walls 6 7, 6' 7', 6" 7", &c., the planes of which when prolonged also pass through the axis 2 3. These movable walls are maintained at a constant distance from each other, 65 being rigidly connected together. It follows that if the movable wall 6 7 approaches the fixed wall 4 5 of the body 1 the walls 6' 7' 6" 7" will approach the walls 4' 5' 4" 5" at the same time. The whole system of movable 70 walls is connected to a point 10, which in turn is connected to a crank 11 12 by the connecting-rod 10 11, Fig. 3. Crank 11 12 is connected to the body 1 at the point 12. Supposing, for an instant, that the body 1 is stationary and that steam be introduced between the walls 4 5 and 6 7, the pressure of the steam will, as in an ordinary cylinder, move the wall 6 7 away from the wall 4 5 of the cylinder, and if steam be then introduced 80 between 4" 5" and 6 7 the wall 6 7 will be displaced in a reverse sense to the first displacement. It will be the same when steam is introduced on either sides of the other walls or pistons 6' 7', 6" 7", and 6" 7".

85

The point 10, mentioned above, will participate in the reciprocatory motion of the whole system of pistons 6 7, 6' 7', &c., and it is easy to conceive that this reciprocatory motion of point 10 will cause a rotation of the 90 crank 11 12 through the intermediation of the connecting-rod 10 11.

Now let us consider two circles, of which the centers are respectively 2 3 and 8 9, Fig. 4. Let us take a line X Y through the centers 95 and let us take a point on each circumference, 12 and 13, for instance. When these two points are joined, it will be easy to demonstrate that if circle 2 3 is made to rotate then circle 8 9 will also rotate, the line 12 13 remaining parallel with itself in all its positions. When circle 2 3 has completed one

100

revolution, the point 13 will have described around point 12 a circle with the radius 12 13. Let us take point 10 on circle 2 3 and trace the connecting-rod 10 11 and the crank 11 12, 5. Fig. 5. When steam is allowed to act alternately on the opposite faces of the pistons 6 7, 6' 7', &c., the point 10 will receive a reciprocatory motion and will cause the crank 11 12 to describe a circle, and if the two cranks 10 11 12 and 12 13 are fixed in the same perpendicular axis to the paper it is clear that the point 13 will be forced to move on the circumference 8 9 in an opposite direction to the movement communicated to the crank 11 12 15 by the point 10.

From the above it can be seen that the two circles 8 9 and 2 3 make the same movement, while the point 10 receives a reciprocatory movement and describes during its motion a 20 segment of a circle with a variable speed if the speed of rotation of these circles is constant. We thus obtain a transmission of reciprocating motion into circular motion. At first sight it will appear as if a force were 25 made to act without a point of support; but by decomposing the acting forces it is clear that the movement is obtained by the aid of the two fixed points of support 8 9 and 2 3. If the centers 8 9 and 2 3 coincide, the movement 30 will be impossible.

Let us now consider a circle having 2 3 as center and 2 3 12 as radius, Fig. 6, and two gear-wheels of which the one has for center 2 3 and for radius 2 3 14 and the other for 35 center 12 and radius 12 14.

Let us again take point 10, connecting-rod 10 11, and crank 11 12, fixed on the same axis as the gear-wheel 12 13. If a rotative movement is communicated to crank 11 12, the gear-wheel 12 13 will take part in the movement, 40 and if gear-wheel 2 3 14 be stationary the point 12 will describe a circle round 2 3 as a center. From this it can be seen that by the gearing of two gear-wheels, one of which is 45 fixed, we obtain a result similar to that obtained by the connecting-rod and cranks, that is to say, the rotatory motion of the body in which steam is allowed to act.

Having thus stated the theory underlying 50 my invention, I will proceed to describe the same in connection with the engine shown in Figs. 7, 8, 9, and 10.

The engine is supported in a frame consisting of a bed-plate and two standards A and B. 55 On the standard A is supported a stationary eccentric D, on which, turning loosely, is mounted a connecting-rod with two arms V, which is attached to the body of the engine by two trunnions T T'. The arm of the connecting-rod connected with the trunnion T' can be dispensed with, but it is preferable to 60 construct the connecting-rod with two arms, so as to increase and equalize the effect. A shaft I J passes through eccentric D and standard A, abutting in the escapement-box F. Shaft I J is supported at its other end in bearings l on the standard B and passed

through the stuffing-box m. At the part I the shaft is hollow, while it is solid at the part J. Keyed to shaft I is the cylinder C C'. 70 This cylinder is divided into three parts, each forming a distinct steam-cylinder and provided with a piston which is made integral with the sleeve P. The cylinder is made of two semisections, which are connected together after the pistons have been inserted into the respective compartments of the cylinder C C'. 75

M and M' are two spindles which carry two cranks K and K', that are connected with the 80 trunnions T T'. On trunnion T is set the head of a connecting-rod L, which controls the three pistons by the intermediation of the crank Q, that is rigidly attached to the end of the sleeve P. 85

N N are packing-rings between the faces of the cylinder-section C and the sleeve P. The stuffing-box P' forms the packing-joint between the faces of the cylinder-section C' and sleeve P. In crank Q we have the point 10, 90 mentioned above, the connecting-rod L corresponding to the line 10 11 and the whole T K M to the lines 11 12 and 12 13. The point O, while partaking of reciprocatory motion, which is transmitted to it by the sleeve P 95 and the piston mounted thereon, compels the cylinder C C' to keep up its continuous rotary motion for the reasons given above. The steam enters from the boiler by the pipe O', passing through a valve actuated by a suitable governor. (Not shown in the drawings.) From pipe O' the steam passes into a chamber O'', through which the shaft I J passes, and thence into the steam-chest U between the hollow shaft X and the shaft I J. In this 105 chest U is arranged a valve, the face of which is in contact with the face of the cylinder, the face of the latter being provided with ports e e' e'', Fig. 9, corresponding in pairs with the compartments in the cylinder, e e' corresponding with the first compartment, e'' e'' with the second, and e''' e''' with the third compartment. Additional ports s s' s'' serve to form 110 communication between the ports e e' e'', &c., and the hollow shaft I by the intermediation 115 of the valve and thus permit of the escape of the steam.

Fig. 10 shows the face of the valve, which has a circular opening r, which coincides with the ports s s' s''. The ports i i' i'' serve for 120 the introduction of the steam, and the ports n n' n'' for the exhaust of the same. The ports i i' i'' and n n' n'' are opposite the port-holes e e' e''. The ports n n' n'' communicate directly with the circular opening r, as shown 125 in Fig. 8.

To effect the proper distribution of the steam, the valve must make a third of a rotation for every full rotation of the cylinder C. We effect this by a train of transmitting 130 gear-wheels W W' W'' W''' or in any other desired manner.

When port i coincides with port e, steam is introduced at e e' e''' and escapes at e' e''

e""". When the cylinder has made a semi-revolution, port *e* coincides with the exhaust-port *n*. After a further semirevolution steam will be introduced anew while coinciding with 5 *i'*, &c. A stuffing-box *u* on steam-chest *U* effects the hermetic sealing of the same.

When steam is supplied through the live-steam ports to the compartments of the cylinder, it acts on the stationary partitions *C*² 10 of the cylinder and on the movable pistons *P*² in the same, moving the cylinder in one direction and the pistons in the opposite direction until the steam supply is cut off. This will move the cylinder and the parts 15 connected therewith through one-half of a rotation, while the pistons move in opposite directions thereto from the partitions at one end of the compartment toward the partitions at the other end of the same. The sleeve *P* 20 and crank *Q* partake of this motion, while the crank *K*, owing to the connecting-rod *L*, describes by the joint action of the same and of the rotary motion of the cylinder a full rotation on the pivot *M*, the arm *V* moving simultaneously 25 with the crank *K* around the stationary eccentric *D*. The parts are moved, therefore, from the position shown in Fig. 11 to the position shown in Fig. 12, in which the crank *K* has moved from its uppermost position into the position at the lowermost part 30 of the cylinder, while the remaining parts assume the position shown, respectively, in dotted lines in Figs. 11 and 12.

The momentum imparted to the cylinder 35 by the live steam completes the remaining half of the rotation of the same, so that the steam is exhausted from the compartments and the pistons and all the parts connected therewith returned into the former position 40 shown in Fig. 11, the motion of the pistons being the reverse of the motion of which they partake under the action of the live steam. The individual movable parts of the engine act conjointly during each full rotation of 45 the cylinder, while each part partakes of the specifically-described motions explained in connection with the diagram Figs. 1 to 6, these diagrams being necessary for the clear understanding of the proper motions. The 50 full rotation of the cylinder having been made, the rotary slide-valve is turned for one-third of its rotation, so that live steam is again supplied to the live-steam ports of the cylinder, the same moved again through one-half 55 of a rotation by the action of the steam on the stationary partitions of the cylinder and the movable pistons, the remaining one-half of the rotation being again completed by the momentum imparted to the cylinder, so that 60 during the first half of the rotation the pistons are moved in a direction opposite to the motion of the cylinder through one-third of the circumference of the same, while during the second half of the rotation of the cylinder 65 the pistons are moved in a direction opposite to their former motion, but in the direction of motion of the cylinder, again

through one-third of the circumference of the cylinder. The rotary slide-valve is then moved again through another third of its revolution and new steam again supplied to the compartments of the cylinder, so that the same makes another rotation, and so on. 70

Compared with straight-cylinder engines my improved engine has the advantage of 75 having a continuous motion in the same direction. Compared with rotary engines it has the advantage of having a movable cylinder, which thus practically constitutes a fly-wheel, so that the latter can be omitted. 80 In addition thereto the cylinder serves also as a driving-pulley. Further, the wear and tear of the machine are less than in ordinary machines, as all the parts are centered.

Having thus described my invention, I 85 claim as new and desire to secure by Letters Patent—

1. A rotary engine, consisting of a cylinder having interior partitions forming compartments, a piston in each compartment, a hollow shaft concentrically to the cylinder, a sleeve mounted on the shaft and connected with said pistons, a crank on the outer end of said sleeve, a crank on said cylinder, a connecting-rod between said cranks, a stationary eccentric, a connecting-rod mounted loosely on said eccentric and pivoted to the crank on the cylinder, a steam-chest on the cylinder, and an independently-rotating valve in said steam-chest, substantially as set forth. 90 95 100

2. A rotary engine, consisting of a cylinder having interior partitions forming compartments, a piston reciprocating in each of said compartments, a sleeve mounted on the shaft of the engine and carrying said pistons, 105 a crank attached to the outer end of said sleeve, cranks arranged at diametrically opposite points on the cylinder, a connecting-rod between the crank on said sleeve and one of the cranks, a stationary eccentric, connecting-rods pivoted to said cranks and mounted loosely on said eccentric, and a valve for controlling the admission and escape of steam to the compartments of said cylinder, substantially as set forth. 110 115

3. In a rotary engine, the combination, of a cylinder partitioned internally to form compartments and provided with admission and exhaust ports for each compartment, with a circular valve set in a steam-chest and mounted loosely on the shaft supporting the cylinder, said valve being likewise provided with inlet and outlet ports to correspond to the ports of the cylinder and with an exhaust-channel in said shaft, and means for rotating the valve, at less speed than the cylinder, substantially as set forth. 120 125

In testimony whereof I have signed this specification in the presence of two subscribing witnesses.

EDMOND CHABOCHE.
